WALL-PLUG.

No. 903,459.

Specification of Letters Patent.

Patented Nov. 10, 1908.

Application filed November 7, 1907. Serial No. 401,120.

To all whom it may concern:

Be it known that I, FRANK L. DYKEMA, a citizen of the United States, residing at Grand Rapids, in the county of Kent and State of Michigan, have invented new and useful Improvements in Wall-Plugs, of which the following is a specification.

My invention relates to wall plugs designed for insertion in concrete or masonry walls and intended to receive and hold a nail driven thereto, and its object is to produce such a device in an especially cheap and effective form.

In the drawings Figure 1 is a top plan view of the sheet metal blank from which a preferred style of my plug is formed up. Fig. 2 is an edge view of the same after forming and from the side, which is the lower side in Fig.

1. Fig. 3 is a sectional view after forming taken on line $x-x$ of Fig. 1. Fig. 4 is a sectional view on the line $y-y$, and Fig. 5 is a sectional view on line $z-z$ of Fig. 1. Fig. 6 shows a modified form of construction.

The device can be made from any suitable material, but I prefer to use sheet metal, and by so doing I can form the entire device from one piece if I wish, and stamp it into complete shape with not more than two operations.

30 Fig. 1 shows the blank. It is preferably of rectangular form. Putting this blank into suitable dies, I cut notches in the sides, as at 19, 21, and slit the metal on all the solid lines shown in this figure; that is, by short longitudinal cuts at the rear (left) end of dotted lines $a-c$, by transverse cuts not extending to either edge, as at 1, 3, 5, 7, 9, 11, 13, and by short longitudinal cuts intersecting the ends of 13, as at 15, 17. Then, preferably by continuance of the same operation, I turn the lips 26 and 28 downward upon the folding lines $f-g$ so that these lips assume the form shown in Fig. 3. At the same time the alternate strips 14, 16, 18, 22, and also, if desired, 40 12 and 24, which strips, after the cutting, have free sides but attached ends, are drawn respectively up and down so that they take longitudinally the form indicated in Figs. 4 and 5, and so that they take, transversely of themselves, at their central portions the form indicated in Fig. 3. In this Fig. 3 the dotted horizontal line represents the lower edge of the lip 4, or that part of the blank connecting at their ends the strips 55 14, 16, etc., and it is apparent that the strips

in their central portion are forced one above this central line and the next below such central line, and are so tilted or inclined that their rear edges are nearer to the central line than their forward edges are. Then, and I 60 believe preferably, by a distinct and subsequent operation, I fold the metal upwardly on dotted lines a , b and c , thus forming upright flanges 2, 4 and 6, and also fold the metal upwardly on dotted line d , thus forming the 65 upwardly-extending connecting or spacing flange or neck 8, and also fold the metal downwardly on the folding line e , thus forming the depending guard and guide-plate 10. All the parts then have the relative positions 70 shown in Figs. 2 and 3.

In the form shown in Fig. 6 I make the guide plate 10 from a separate piece, although this may be cut from the same blank, in which case the cut would be along lines 75 like the solid lines in Fig. 6. I then fasten the guide plate to the body of the plug, and at approximately right angles thereto, by any suitable means, as, for example, by folding the ends of flanges 4 and 6 over on the dotted 80 lines 23, 25 so that they embrace and hold the plate 10 when it is severed and put in position, the points of embracing and holding being shown by 27 and 29.

After my plug is formed as so far described, 85 I intend to coat it with paint, tar, or other preservative material, and if such material fills the openings between strips 14, 16, etc., or partially fills the same, and remains there, it will do no harm, but will be of advantage 90 in excluding mortar or concrete.

In the building of a wall this plug is inserted at the desired spot. The concrete or mortar sets against the exterior of strips 14, 16, etc., and to some extent also upon the other 95 side of such strips. On account of the way in which the mortar or concrete will thus enter and set within the outwardly-extending edges of strips 14, 16, etc., and on account of the inclination of these strips such 100 that an outward pull tends to force them still farther up or down into the concrete or mortar, it is substantially impossible that one of these plugs should be displaced from its position in the wall, and it is quite impossible 105 that when an outward strain is exerted upon the plug, its retaining parts should yield towards the center so as to permit it to slip forward out of the wall, but as the outward pull increases, the resistance will increase. When 110

the plug is thus in position it is ready to receive the nail which will be driven through the material which it is desired to attach to the wall. The opening in plate 10 formed by the lips 26, 28 will receive the point of the nail and it will be guided into the opening between strips 22 and 24 and so will follow along substantially the line indicated by the horizontal dotted line in Fig. 3. If this interior space is filled with paint, tar, or some similar material, this will not impede the entry of the nail; and in any event, under practical conditions, the mortar or the concrete will not enter between the strips so completely as to interfere with the driving of the nail. The device will be so constructed that either in its original form or by the pressure exerted by the surrounding material, the strips 14, 16, etc., will be close enough together so that the nail on its entry must force them to yield; and it will follow that the rear edge of each strip will be forced against the nail with considerable pressure. On account of the inclination of these strips, as shown in Fig. 3, the rear edges will thus yield when the nail is driven inwardly, but when there is an outward pull upon the nail they will not only not yield, but will tend to grasp the nail more firmly and the sharp edges left by the ordinary process of cutting, will bite into the sides of the nail in such a way that no ordinary strain can pull it out.

When the nail is driven in so that the head of the nail strikes the guide-plate 10, such head will not pass through the opening therein, which should not be large enough to permit such passage; but as the driving process is continued, the guide-plate 10 will be bent back flat upon the neck 8 against the face of the wall, or will be held out at a predetermined distance from the wall just according to the shape and resisting strength of the flange or neck 8. Obviously in the form shown in the drawings, the base of this flange or neck 8 will operate as a stop against the face of the wall, and it could be so constructed, as for example by making it of material which would not yield or bend further under the ordinary hammer stroke, that it would hold the head of the nail out away from the face of the wall at the same distance shown in Fig. 3, or at any predetermined distance.

I have found that this wall plug is exceedingly cheap to manufacture and having no opposite or facing walls which may collapse or yield toward each other and reduce the diameter or thickness of the device, it is therefore particularly efficient; and I also find that its means of engaging the driven nail constitute a feature of distinct advantage. It is evident also that the essential feature of the invention is to cause these transverse strips to bite or bind against the nail sufficiently to prevent its accidental removal, and that by drawing these strips alternately up and down

or in reverse directions with respect to the plane of the plate, as shown by the preferred form of the device selected for illustration, a materially better result is obtained than if a less number of strips were used and drawn in one direction only.

Having thus described my invention, what I claim to have invented, and desire to secure by Letters Patent, is—

1. A wall plug comprising a metal plate, means whereby such plate may engage the wall in which it is embedded, means whereby the nail may be held centrally and longitudinally in such plate, alternate portions thereof being above and below such nail, a guide-plate at substantially right angles to the main plate, which guide plate has an opening to receive and guide the point of the nail and to retain the head of the nail, and means for uniting such guide-plate to such main plate.

2. A wall plug comprising a metal plate, means whereby such plate may engage the wall in which it is embedded, means whereby the nail may be held centrally and longitudinally in such plate, alternate portions thereof being above and below such nail, a guide-plate at substantially right angles to the main plate, which guide plate has an opening to receive and guide the point of the nail and to retain the head of the nail, and a connecting flange or neck uniting such guide-plate to such main plate.

3. A wall plug comprising a metal plate and a plurality of partially severed transverse strips having their ends connected to such plate and their central portions separate from the plate and outside the plane thereof, whereby the entering nail may be received and gripped by the central portions of the strips, and means carried by the plate for holding the plug at the face of the wall.

4. A wall plug comprising a metal plate and a plurality of partially severed resilient transverse strips having their end portions attached to the plate and their central portions drawn away from the plane of the plate, whereby the entering nail may pass under such central portions and be received and gripped upon its side thereby, and means carried by the plate for holding the device at the face of the wall.

5. A wall plug comprising a metal plate and a plurality of transverse strips having their end portions attached to the plate and their central portions separate from the plate and removed, part in one direction and part in the opposite direction with relation to the plane of said plate, whereby the entering nail may pass between the central portions of the oppositely placed strips, and means carried by the plate for holding the device at the face of the wall.

6. A wall plug comprising a metal plate and a plurality of transverse resilient strips

- having their end portions attached to the plate and their central portions separate from the plate and part of the same drawn in one direction and part drawn in the opposite direction from the plane of the plate, whereby the entering nail may pass between the central portions of the oppositely drawn strips, and means carried by the plate for holding the plug at the face of the wall.
7. A wall plug comprising a metal plate having a plurality of transverse partially severed strips integrally attached at their ends to the plate and at their central portions drawn in reverse directions away from the plane of the plate, whereby the entering nail may pass between the oppositely drawn strips, and means carried by the plate for holding the plug at the face of the wall.
8. A plug comprising a metal plate having a plurality of transverse strips, the latter having portions attached to the plate and other portions separated from the plate and at one side of the plane thereof, the rear edges of the strips being inclined closer to the plane of the plate than the forward edges of the strips, whereby the rear edges yield to the entering nail but hold the said nail against removal.
9. A wall plug comprising a metal plate having a plurality of transverse strips out of the plane of such plate, the strips having their forward edges inclined outwardly and away from the plane of the plate, whereby while the rear edges of the strips yield to the entering nail, the forward edges engage with the inclosing material and hold the plate against removal.
10. A wall plug comprising a metal plate having partially severed and transversely expanded metal strips bent to incline inwardly from the front to the rear edges of such strips, whereby the rear edges of the strips yield to the entering nail and hold the said nail against removal, while the front edges of the strips engage with the inclosing material and hold the plate against removal.
11. A wall plug comprising a metal plate having a plurality of transverse strips, the strips having their ends attached to the plate and their central portions drawn away from the plate partly in one direction and partly in the opposite direction, the strips being so inclined that their rear edges are least removed from the plane of the plate, whereby said rear edges of the strips yield to the entering nail but hold the said nail against removal.
12. A wall plug comprising a metal plate having partially severed and transversely expanded metal strips drawn respectively in opposite directions from the plane of the plate and inclined rearwardly, the rear portion of each strip inclining toward the plane of the plate and the forward portion thereof inclining away from the plane of the plate, whereby the rear portions of the strips yield to but hold the entering nail respectively upon opposite sides thereof and the forward portions of the strips engage with the surrounding material respectively upon opposite sides of the plate and hold the plate against removal.
13. A wall plug comprising a metal plate and a plurality of partially severed transverse strips having their ends connected to such plate and their central portions separate from and outside the plane of the plate, whereby the entering nail may be received and gripped by the central portions of said transverse strips, and means carried by the plate for receiving and guiding the nail to a central position.
14. A wall plug comprising a metal plate having a plurality of transverse partially severed strips integrally attached at their ends to the plate and at their central portions drawn respectively in reverse directions away from the plane of the plate, whereby the entering nail may pass between the oppositely drawn strips, and means carried by the plate for receiving and guiding the nail to a central position.
15. A wall plug comprising a metal plate having partially severed and transversely expanded metal strips bent to incline inwardly from the front to the rear edges of such strips, whereby the rear edges of the strips yield to the entering nail and hold the same against removal, the front edges of the strips being adapted to engage the inclosing material and hold the plate against removal, and means carried by the plate for receiving and guiding the nail to a central position.
- In testimony whereof I have hereunto set my hand in presence of two subscribing witnesses.
